DONALD F. LYMAN, OF ROCHESTER, NEW YORK, ASSIGNOR TO EASTMAN KODAK COMPANY, OF ROCHESTER, NEW YORK, A CORPORATION OF NEW YORK.

MOTION-PICTURE-FILM SPLICE.

Application filed January 22, 1927. Serial No. 162,772.

This invention relates to splices for motion picture film, and particularly to splices of the type wherein two sections of film of plastic cellulosic composition are united by a solvent or cement to form a unitary, welded or substantially homogeneous joint or union.

When such splices are properly made they seldom fail by reason of the separation of the cemented surfaces. There are, however, certain causes of failure which are particularly potent at the splices. Because of the double thickness of the film throughout the width of the strip, it is stiffer at this point and this causes excessive bending at the ends of the double or stiff portion when the film passes around sprockets or loop paths of small radius. The gates, sprockets, and guideways of motion picture apparatus usually engage the film at the borders only and these constitute traction and wear taking portions. The central part of the mechanism between the border engaging portions is usually undercut so that the picture area of the film does not contact the apparatus. Moreover, the guideways frequently comprise pressure members which engage both surfaces of the borders of the film and must be forced apart when a double thickness of film is encountered.

One object of my invention is to furnish a splice that is easy to make, and that is flexible. A further object is to furnish such a splice which, while strong and enduring, is of single thickness at the borders where greatest flexibility is desired, and where pressure guideways are engaged. These and other objects are attained by splices made in accordance with the following description and embodying the inventions pointed out in the claims.

Reference will be made to the accompanying drawing in which the same reference characters designate the same parts throughout and in which

Fig. 1 shows two sections of film united by my improved splice;

Fig. 2 is a side view of such a splice;

Fig. 3 is a section on the line 3-3 of Fig. 1;

Fig. 4 is a transverse section of a film guideway with film embodying my improved splice therein;

Figs. 5, 6, and 7 show other embodiments of my invention;

Fig. 8 is an edge view of the splice shown in Fig. 7;

Fig. 9 shows still a different embodiment of my invention;

Fig. 10 is an edge view of Fig. 9; and

Fig. 11 shows still another embodiment of my invention.

In each of the various figures there is shown a film strip, meaning an assembled length of film comprising more than one section of film, of which are shown two sections and the splice by which they are joined. The thickness is shown on exaggerated scale.

The preferred form, which is also the simplest, is illustrated in Figs. 1 to 4. The film here shown is of the type now marketed in a small size having a uniformly spaced series of perforations 1 along each border 2. The perforations are in pairs opposite each other; there is one pair of perforations to each picture area A and having a definite position with respect to the corresponding area. It is very seldom that there is cause to splice unexposed film, so that in making splices the film being handled almost invariably is no longer sensitive and carries photographic images. The two sections 3 and 4 of film are accurately located during assembly so that this uniformity continues past the splice. The ends of the film to be joined are cut into a tapered form as shown in Fig. 1. I have noticed that when the cuts are made with shears, that is, between two cutting edges, as distinguished from cutting from one side by a knife or blade against a flat surface, that the resultant splice is very much more durable, apparently because the latter method leaves a ragged edge on one side from which tears tend to start. The tapered ends have, preferably, angular sides 6 terminating in a bluntly rounded apex 7.

Each of the films comprises a support 8 of a plastic cellulosic composition, such as one of cellulose acetate, cellulose nitrate, cellulose ether or the like, upon one surface of 5 which is a colloid layer 9, usually gelatine, customarily having a photographic image.

The gelatine layer is scraped away as at 10 from the end of the tapered portions of section 3 and a common solvent or a cement 10 is applied to the support as thus bared. The bottom of the support 8 of the other section 4 is at once placed on the scraped portion 10 and held under pressure until the overlapping ends unite. In this type of 15 joint or splice there is involved the action of the solvent or cement upon the material of the two supports to be united, first attacking or dissolving a portion of the material and forming a fluid or plastic zone 20 between the two supports, which upon evaporation of the solvent becomes a zone of interunion between the two, integral or homogeneous with both. This method is known, and in order to distinguish it from 25 other methods of uniting such layers, such as by the action of a merely adhesive material or by the use of metallic fasteners, I shall designate it as a splice of the welded type.

30 The extent of the overlap 5 is less than the complete tapered portion but provides a joint or splice of sufficient area and strength to withstand any ordinary usage. There is thus left at each edge of the strip 35 a notch 11 opposite the splice. This notch preferably extends across the film a distance greater than the border portion 2 defined between the edge of the film and the edges of the picture areas A, the latter line also 40 being that of the inner edges of the perforations 1. The length of the notch is less than that of a picture area or of the distance between two successive perforations.

45 As shown in Fig. 4, the border portions 2 are the wear resisting portions as the film passes through the motion picture apparatus. There is here shown, in section, a typical guideway having opposed members 12 having edge portions 13 bearing on the film borders and intermediate channel portions 14 not contacting with the film. One of these members 12 is pressed by spring 15, which bears against a fixed frame 16, against the other members which is also 50 fixed so that the film borders are subject to constant resilient pressure. When an ordinary splice passes through such a gate it strikes such a pressure member with objectionable force that is undesirable and noisy. 55 With my improved splice, however, there is 60 at no time more than a single thickness of film along the borders and the doubled overlap portion 5 passes through the channel part of the guideway. Since such guides 65 are frequently curved, as are the sprockets

which also engage the film at the borders only, the film can follow these readily, the edges being flexible, and the film as a whole is not bent and broken.

Forms of the splice particularly designed for use with standard motion picture film having four perforations 21 to each picture area B are shown in Figs. 5 and 9 to 11. In the form shown in Fig. 5 the edges of the tapered portions are cut in compound curves 75 22 so as to avoid cutting through perforations, providing a welded overlap 23 and edge notches 24 analogous to those previously described, and attaining the results desired. In Figs. 9 to 11, the cuts are first perpendicular to the edge as at 23' then longitudinally of the film strip as at 24' and then transverse of the film again at 25', being cut 80 symmetrically from both edges. There are thus formed tabs 26 which may be overlapped as shown, either leaving a space or notch 27 of some width as in Figs. 9 and 10, or almost abutting as at 28, Fig. 11. In every case, however, the cuts avoid the perforations, overlap is entirely within the picture 85 area, and the uniformity of the picture areas and perforations is not disturbed. Every fourth perforation, it is to be noted, has the same relation to corresponding picture areas and the length of the notch is less than the distance between such corresponding 90 fourth perforations.

95 It is not necessary that the tapered ends of the sections be symmetrical. As shown in Fig. 6, one inclined edge 30 of each tapered portion is shorter than the other 31, and is cut at a different angle there being produced an unsymmetrical overlap 32. Notches 33 analogous to notches 11 are thus formed.

100 The doubled portion may be made, moreover, by a separate patch piece as shown at 40 in Fig. 7. In this case, the end of each section is cut with a short angular edge 41 and a long angular edge 42. They are laid 105 with the long edges 42 abutting, thus leaving notches 45 analogous to those previously described, and a separate patch 40 preferably of the same material as the support 8, is laid 110 on the support side of both sections to which it is welded, united or cemented by the 115 method already described to form a splice such as I have already defined as "welded." The ends of the patch are preferably rounded as at 43. This form of splice has the advantages that the surface, opposite the patch 120 lies in the same plane throughout, and the film is not subject to distortion in passing through a guideway, and that it is not necessary to perform a scraping operation to any 125 surfaces, if the patch is applied as described.

Having thus described my invention, what I claim as new and desire to secure by Letters Patent is:

130 1. A motion picture film strip comprising longitudinally aligned sections of film of a

cellulosic plastic material and having a definitely defined, longitudinally extending, wear taking portion over a part of its width, and a splice of the welded type joining the 5 ends of the sections and extending over only a portion of the width of the film outside of the wear taking portion.

2. A motion picture film strip comprising longitudinally aligned sections of film of a 10 cellullosic plastic material having at each edge a longitudinally extending, wear taking portion, and a splice of the welded type uniting the ends of the film sections only between the wear taking portions.

15 3. A motion picture film strip comprising two longitudinally aligned sections of film of a cellullosic plastic material having at each edge a longitudinally extending, wear taking portion, and a splice of the welded type 20 uniting the ends of the sections only between the wear taking portions, the ends of the wear taking portions being cut at acute angles, whereby V shaped notches are formed in the edges of the strip opposite the 25 splice.

4. A motion picture film strip comprising two longitudinally aligned film sections with overlapping end portions tapering in width, the extent of the overlap being materially 30 less than that of the tapered portions, whereby V shaped notches are formed in the edges of the strip opposite said overlap, and the overlapping portions being united.

5. A motion picture film strip comprising 35 two longitudinally aligned film sections of cellullosic plastic material, and with uniformly spaced perforations along at least one border, said border constituting a wear resisting portion, and a splice of the cemented type uniting the ends of the sections and extending only over a portion of the film strip and out of alignment with said border.

6. A motion picture film strip comprising 45 two longitudinally aligned film sections of cellullosic plastic material having along each border a row of uniformly spaced perforations, and a splice of the welded type uniting the ends of the sections between the 50 perforations only, the ends of the border portions of the sections being cut at acute angles to the edges whereby V-shaped notches are formed in the edges of the strip opposite the splice.

55 7. A motion picture film strip having along at least one border a series of uniformly spaced perforations and comprising longitudinally aligned film sections joined at their ends by a splice of the welded type, extended 60 over a portion only of the width of the strip, there being in the strip in line with the perforations and opposite the splice a notch shorter than the distance between successive perforations.

8. A motion picture film strip having a

longitudinal series of uniform image areas and along each border a series of perforations, there being a perforation in each border at a definite relation to each picture area, the strip comprising longitudinally aligned 70 sections of film having tapered end portions overlapping and united for a distance less than the length of the tapered portion, whereby notches are formed in the borders opposite the overlap, the notches being shorter than the distance between the perforations corresponding to successive picture areas.

9. A motion picture film strip comprising longitudinally aligned sections of film of cellullosic plastic material having longitudinally 80 extending, wear taking border portions, and a series of uniform fields with images thereon between said borders, the sections being united between said borders by splices of the welded type and the ends of the border portions of the sections being separated by notches opposite the splice having a length less than the length of an image bearing field.

10. A motion picture film strip comprising 90 longitudinally aligned film sections with uniformly spaced perforations along their borders and a longitudinal series of fields of uniform size with images thereon between said perforations, the sections having tapered, 95 united, overlapping end portions, the extent of the overlap being less than that of the tapered portions, whereby V shaped notches are formed in the edges of the strip opposite the overlap, each notch having a length less than 100 the length of an image field and extending across the strip at least the full width of the corresponding perforations.

11. A motion picture film strip having defined wear taking border portions and an 105 exposure area between such border portions, and comprising longitudinally aligned sections of film, the borders of the strip having at all points a thickness not greater than a single thickness of film, and the sections 110 having united; overlapping ends in the exposure area only.

12. A motion picture film strip comprising two sections of film having border portions of uniform width and having perforations 115 spaced uniformly longitudinally of said border portions, the space between said border portions constituting an exposure area of uniform width longitudinally of the film, the two sections lying in longitudinal alignment with their meeting ends overlapping and cemented together, the distance between perforations in the region of the meeting ends being the same as the uniform distance between perforations along the film 120 sections, the sides of the meeting ends of said sections being similarly tapered from the extreme edges to points within the exposure area, whereby each section has a symmetrically tapered end, the overlapping por- 125 130

tions of the film ends being limited to the extreme ends of the tapered portions lying within the exposure area, whereby there is left on each edge of the united film strip a notch opposite the overlapping area extending entirely across the border portion, the longitudinal dimension of said notch being less than the distance between successive perforations.

10 Signed at Rochester, New York this 18th day of January, 1927.
